[57] CLAIM

I claim the ornamental design for package having fabric wrap, with fabric having printing on two sides, as shown and described.

DESCRIPTION

FIG. 1 is a perspective view of a first embodiment of the claimed design, showing a rectangular package having fabric wrap, the fabric having printing on two sides.

FIG. 2 is a top view of the design of FIG. 1.

FIG. 3 is a side view thereof, both sides being substantially identical.

FIG. 4 is an end view thereof, both ends being substantially identical.

FIG. 5 is a bottom view of the design of FIG. 1.

FIG. 6 is a top view of a second embodiment of the claimed design, showing a cubic package having fabric wrap, the fabric having printing on two sides.

FIG. 7 is a side view thereof with other sides being substantially identical.

FIG. 8 is a bottom view thereof.

FIG. 9 is a top view of a third embodiment of the claimed design, showing a cylindrical package having fabric wrap, the fabric having printing on two sides.

FIG. 10 is a side view thereof the opposite side being substantially identical.

FIG. 11 is a bottom view thereof.

The surface ornamentation on the fabric is illustrative of printing on two sides of the fabric and not part of the claimed design.
